UNITED STATES PATENT OFFICE

JOHN R. STEWART, OF COLUMBUS, OHIO

WINDOW SASH MOUNTING

Application filed April 9, 1929. Serial No. 353,801.

This invention relates to improvements in window sash mountings, and has for an outstanding object the provision of a sash mounting in which both the top and bottom sashes of the window are counterbalanced and mounted for vertical sliding movement in the conventional manner, but wherein provision is made in the construction of the mounting to admit of inward swinging movement about substantially horizontal axes of both of the sashes in order that the latter may be positioned within the confines of a room for the purpose of facilitating the washing and cleaning of the transparent panels of said sashes.

It is a difficult and often physically dangerous task to wash the exterior surfaces of ordinary window sashes and constitutes a source of considerable expense especially in the up-keep of public or semi-public buildings. It is customary to employ experienced operators for the specific purpose of periodically cleaning the windows. A large part of this expense may be attributed to the difficulty encountered in cleaning the outer surfaces of the windows and to the hazardous character of the operation. It is, therefore, the principal purpose of the present invention to permit of the washing of the windows from positions within the building in which the windows are mounted in order to permit the work to be more thoroughly and expeditiously accomplished and, if desired, by inexpert labor with accompanying low costs.

It is another object of the invention to provide a sash mounting wherein provision is made for locking the sashes in a horizontal plane when the latter are swung inwardly to admit of their cleansing, the locking being accomplished automatically through swinging movement of the sash or sashes in order to avoid the necessity of manually holding the sashes in a fixed position during the cleansing operation.

A further object of the invention resides in the provision of means for weather stripping the various relatively movable members comprising the sash mounting in order that the construction would be weather-tight and secure against rattle and vibration.

It is still a further object of the invention to provide means in connection with the mounting whereby the sashes may assume partially open or inclined positions with respect to the vertical, in order to admit of proper and adequate ventilation of the rooms without creating undesired drafts.

It is another object of the invention to provide means for locking the sashes in their partially open or ventilating positions.

The invention also has for further general objects the provision of a sash mounting of simple, light weight and durable construction which is not apt to become out of order or to require undue attention or adjustment to maintain the same in proper working order, the mounting possessing substantially the simplicity and freedom from repair as is present in window constructions of conventional design but with, of course, the above added features of advantage.

With these and other objects in view, which will appear as the description proceeds, the invention consists in the novel features of construction, combinations of elements and arrangements of parts hereinafter to be more fully described and pointed out in the appended claims.

In the accompanying drawings:

Figure 1 is a view in front elevation of a pair of window sashes mounted in a window frame by the structure comprising the present invention,

Figure 2 is a vertical sectional view on the plane indicated by the line 2—2 of Figure 1, illustrating by the dotted lines the sashes in partially open positions,

Figure 3 is a horizontal sectional view taken on the plane indicated by the line 3—3 of Figure 1,

Figure 4 is an edge elevation of the sash mounting, illustrating the sash proper in a horizontal position,

Figure 5 is a vertical sectional view on the line 5—5 of Figure 4, disclosing the structure for securing the sash cord to the mounting,

Figure 6 is a horizontal sectional view taken on the plane indicated by the line 6—6 of Figure 4, showing the frictional lock in a clamping position for retaining the sash in

movably vertical positions when fully lowered.

Figure 7 is a similar view disclosing the lock in a released position,

5 Figure 8 is a vertical section through the lock on the plane indicated by the line 8—8 of Figure 4,

Figure 9 is a detail perspective view of one of the channel members of the sash mounting,

10 Figure 10 is a horizontal sectional view on the line 10—10 of Figure 9, disclosing the lock for retaining an associated sash in a fixed ventilating position,

15 Figure 11 is a vertical sectional view on the line 11—11 of the ventilating lock,

Figure 12 is a perspective view of the spring latch of the ventilating lock, and

20 Figure 13 is a perspective view of the several members comprising the frictional 25 clamping lock for retaining the sash in a horizontal or clamping position.

Referring more particularly to the drawings, the numeral 1 designates the frame structure of the window. This frame structure may be substantially conventional in design and is provided with the usual sill or ledge 2, vertical side walls 3—3 and a top sill 4, which are shaped and positioned to produce the usual rectangular opening for the reception 30 of the vertically slideable upper and lower window sashes 5 and 6 respectively. The side walls 3 are provided with transversely spaced vertically extending guides 7 which form channels 8 in connection with which the 35 sashes are guided for sliding movement in vertical planes.

To effect the mounting of the sashes in such manner that the latter, in addition to the customary vertically sliding movement, may 40 be swung inwardly and rocked about horizontal axes, the present invention provides a mounting for each sash which includes a pair of vertically disposed channel members 9. These members are arranged to occupy the 45 vertical guide channels 8 and to slide vertically therein. The channel members are preferably formed from a light weight metal such as an alloy of aluminum and in the present instance each of said members consists of 50 a pair of sections 10 and 11 provided with flat adjoining faces 12 and 13 which are spot welded or otherwise rigidly secured together to produce a rigid assembly of necessary mechanical strength and yet of unusual cross- 55 sectional formation. The sections 10 and 11 include vertically extending, transversely spaced walls 14 adapted to engage with the vertical guide 7 of the frame structure, and the walls 14 terminate in inwardly directed 60 relatively spaced flanges 15 which engage with the side walls 3 of the frame structure, as is shown particularly in Figures 3, 6 and 7.

Since the channel members are mounted for sliding movement in the channels 8 it is desirable to exclude the weather by the provi-

70 sion of vertical weather strips 16. These strips are directly secured to the side walls 3 and have their free or resilient vertical edges disposed for frictional engagement with the inner surfaces of the flanges 15. This provides a simple and convenient method of preventing the passage of the elements through the joints existing between the movable channel members and the window frame structure.

75 It will be observed that the channel members 9 are of such thickness that their inner portions project beyond the guides 7 in order that said guides will not interfere with the swinging movement of the sashes about horizontal axes. To effect the pivotal mounting 80 of the sashes each of the latter has secured thereto along the full length of its vertical side edges substantially flat metallic strips 85 17 which, when the sashes are in vertical planes, engage closely with the walls 12 of the channel members 9. The lower ends of the strips 17 have welded or otherwise rigidly secured thereto, a pair of trunnion studs 18 for each sash. These studs have been shown particularly in Figures 6, 7 and 13. Each 90 stud is formed to include an enlarged circular head 19 from which projects a cylindrical shank 20. This shank terminates in a non-circular portion 21 and in a diametrically reduced extension 22. The non-circular portion 21 is shaped to be positioned within a correspondingly formed opening formed in a cam element 23, while the extension 22 is received within a small circular opening formed centrally in a clamping plate 24. This plate, 95 as shown in Figure 13 especially and also in Figures 6 and 7, is provided with cam surfaces 25 and with vertical locking shoulders 26, while the element 23 includes laterally turned lips 27 having cam edges 28.

100 By virtue of this construction it will be seen that when the sashes are swung inwardly about the horizontal axes provided by the shanks 20 of the studs 18, the strips 17 move in unison therewith, since said strips are directly secured to the side edges of the window sashes. Then, since the studs 18 are rigidly secured or, if desired, integrally formed with the strips 17 the said studs revolve about their longitudinal axes. This results in the rotation of the cam elements 23 since the latter are mounted on the non-circular portions 21 of the stud shanks 20. The rotation of the cam elements 23 bring the lips 27 thereof into engagement with the cam surfaces 25 of the locking plate 24, forcing said plates outwardly against the resistance exercised thereon by the springs 29 which are carried by the extreme outer ends of the studs 18. This 110 results in bringing the rubber bearing surfaces 30 provided on the plates 24 into frictional contact with the flanges 15 of the channel members 9 or the weather strip 16, as shown in Figure 6, with the result that when the sashes 5 and 6 assume substantially hori- 115 120 125

zontal positions they are frictionally locked against upward movement, since the plates 24 press the flanges 15 of the channel members 9 into firm frictional contact with the side walls 38, creating such friction as to overcome the influence of the sash weights 31 on the channel members 9.

It will be understood that when the sashes are moved to a horizontal position the load which they exercise normally on the weights 31 is lessened. This would result in the elevation of the sashes when the latter assume horizontal positions if the frictional locks were not provided. However, by the inclusion of the locks it will be seen that when the sashes are moved to horizontal or other positions decreasing the load on the weights 31 vertical movement of the sashes in response to the influence of the counterbalancing weights is precluded through the employment of the frictional locking mechanism described. The channel members 9, as shown in Figures 4 and 5, are provided with integral tongues 32 which are received within eyes 33 formed in connection with cable anchors 34. The cables 35 are suitably connected with the anchors 34 and are trained over the usual pulleys in the upper portion of the frame structure and have their lower free ends connected with the sash weights 31 which function in the usual manner to counterbalance the weight of the sashes 5 and 6 when the latter are moved in normal vertical planes.

In addition to the inward swinging movement imparted to the sashes for the purpose of facilitating cleaning thereof or other desired operations, the present invention further admits of the positioning of said sashes so that the latter may be effectively employed for the purpose of room ventilation. In this respect each of the sashes is capable of swinging about the axis provided by the studs 18 to a limited extent so as to be angularly positioned with respect to the vertical. This permits air to enter a room in an upward direction toward the ceiling, preventing the creation of objectionable drafts and other air currents in the room.

To retain the sashes in said positions of partial opening for ventilation use is made of the structure depicted in detail in Figures 9 to 12 inclusive. The section 11 of each of the channel members has its wall or face 13 provided with a vertical recess or groove 36 which is employed to receive a pin 37 carried by the upper end of a link 38. There are, of course, two of these links for each sash, the lower ends of said links being pivotally connected, as at 39, with the sash strips 17. Secured to the rear or inner surface of the walls 13 of each section 11 is a spring lock 40 illustrated in detail in figure 12. This lock includes an enlarged base 41 which is riveted or otherwise fastened to the wall 13 and the

base 41 terminates in a forwardly directed resilient arm 42. This arm projects into the groove 36 and is provided at this point with a pair of reversely inclined integral fingers 43 between which are formed shoulders 44. The finger 42 projects through a slot provided in the inner of the walls 14 in order that said fingers may be rendered accessible for the purpose of manually adjusting or operating the same.

When it is desired to position the lower sash, for example, in a ventilating position the customary turn latch 45, which locks the sashes, is opened. This permits the lower sash to rock about its horizontal axis in an inward direction. Following a predetermined degree of oscillation on the part of the sash the pins 37 provided on the links 38 are moved downwardly in the grooves 36 until they contact with the upper of the resilient fingers 43. Slight further movement results in resiliently operating the arm 42 so that the pins 37 will be positioned between the locking shoulders 44. In this manner the sashes are held locked or secured in their ventilating positions and cannot be further moved until the fingers 43 are manually moved inwardly by operating the exteriorly projecting portions of the arm 42. When this is done the sash may be moved about its horizontal axis either to a position of closure or to a position more fully opening the window. One or more of the catches 40 may be provided in connection with each sash in order to secure a variety of full or partially opened positions.

In view of the foregoing it will be seen that the present invention provides a window sash mounting of simple, readily operated and practical design for attaining the objects of the invention and the features of construction which I have above pointed out. In summary, the invention provides first, for the inward swinging movement of a window sash about a substantially horizontal axis for the purpose of facilitating the cleaning of the glass panel or panels of the sash, permitting this work to be accomplished from within a room and without danger or discomfort to the operator. Second, the invention provides for the provision of automatically operating means for preventing vertical slanting movement of the sash when the latter is being rocked about its horizontal axis to its full opened or extended position within the room. This permits of the use of the ordinary counterbalancing weights for ordinary raising and lowering of the window in vertical planes and yet provides for the turning of the sash about its horizontal axis and the removal of the effective weight of the sash from the counterbalancing weights. Third, the structure is such as to permit of the positioning of the sash in partially opened or turned positions about

said horizontal axis in order to provide for room ventilation and the locking of the sash in such positions of partial opening. Further, the provision of a mounting is afforded which is both light in weight and is capable of being easily and cheaply manufactured.

While I have described what I consider to be the preferred form of my invention from a mechanical standpoint, nevertheless it will be understood that the disclosures and description merely refer to but one of the many possible forms of the invention and I therefore do not desire the following claims to be construed as referring to any one specific structure since it is the intent and purpose thereof to cover the various modifications and mechanical equivalents of the specific structure herein set forth in detail.

What is claimed is:

1. In a window structure, a pair of slide members mounted for vertical movement in connection with the sides of a window frame, a window sash, horizontally disposed studs rigidly secured to the lower portions of said sash and received within bearing openings provided in connection with said slide members, a cam element rotatable with one of said studs, a cam plate carried by the outer portion of one of said studs and movable through the medium of said cam element upon the rotation of said sash and said studs in a direction longitudinal of said studs to force said slide member into frictional holding engagement with the window frame.

2. In a window structure, a hollow metallic slide member formed to include a pair of longitudinally connected sections, said sections being provided with adjoining faces and with spaced inwardly extending side walls terminating in in-turned vertical flanges, one of said sections being vertically grooved throughout the substantial full length thereof.

3. A slide member for window sashes comprising a hollow metallic member, said member being formed to comprise a flat vertical outer wall, side walls extending at right angles to said outer wall, in-turned vertical flanges formed with the edges of said side walls, one of said side walls being provided with a vertically extending groove extending substantially throughout the length of the slide member and opened to one side thereof.

4. In a window structure, a frame formed to include vertically extending guides, a pair of hollow metallic slide members counter-weighted to travel vertically in said guides, said slide members being vertically grooved along one side thereof, a sash disposed between said slide members, metallic strips secured to the vertical side edges of said sash and adapted to lie adjacent to said slide members when said sash occupies a vertical plane of operation, said strips being formed with

in-turned flanges along certain of the edges thereof and adapted to be received within said grooves formed in said slide members when said sash is vertically positioned, and horizontally disposed trunnions carried by the lower portions of said sash and rotatably received within bearings formed in connection with the lower portions of said slide members.

5. In a window structure, a frame provided with vertically extending guides, hollow metallic slide members positioned for vertical travel within said guides, sash counter-weighting devices connected with said slide members, the last one of said slide members being provided with a vertically extending groove open to the inner side of the window structure, a sash arranged between said slide members, means for pivotally connecting the lower portion of said sash with said slide members to admit of the turning of said sash about a substantially horizontal axis, and a link pivotally connected at one end with said sash and having its opposite end adapted for sliding movement within a groove formed vertically within one of said slide members.

6. In a window structure, a frame provided with a window opening having vertically disposed guides located at the sides thereof, hollow metallic slide members counter-weighted for vertical travel in said guides, a sash positioned between said slide members, a horizontal pivotal connection between the lower portion of said sash and said slide members, one of said slide members being formed with a groove opening to the inner side of the window structure, a link pivotally connected at one end with said sash and having its other end slidably received within said groove, and locking means positioned in said groove and cooperating with said link for positively retaining said sash in an angular plane with respect to the vertical.

7. In a window structure, a frame provided with a window opening having vertically extending guides at the sides thereof, hollow metallic slide members mounted for vertical travel in said guides, counter-weighting devices connected with said slide members, a window sash positioned between said slide members, one of said slide members being provided with a vertically extending groove, a pivotal connection between the lower portion of said sash and said slide members admitting of turning movement of said sash about a substantial horizontally extending axis, a link pivotally connected with one end of said sash, an offset pin carried by the other end of said link and receivable within said groove, and resilient means carried by said slide member and formed to lockingly engage said pin when said sash assumes a partly open position, said resilient means being provided with an exteriorly projecting

- portion for facilitating the release of said pin from engagement therewith.
8. In a window structure, a framework formed to include a sash opening, vertical guides provided at the sides of said opening, counter-weighted slide members confined to travel in fixed vertical planes determined by said guides, said slide members being provided with in-turned flanges, resilient weather strips fixed to said framework and provided with flexible edges arranged to engage with said flanges, a window sash, horizontally disposed studs rigidly secured to the lower portion of said sash and received within bearing openings provided in connection with said slide members, a cam element rotatable with one of said studs, a cam plate carried by the outer portion of one of said studs and movable through the medium of said cam element upon the rotation of said sash and said studs in a direction longitudinal of said studs to force the flexible edges of said weather strips into firm contact with the inturned flanges of said slide members.
- 25 9. In a window structure, a framework formed to include a sash opening, vertical guides provided at the sides of said opening, slide members confined to travel in fixed vertical planes determined by said guides, said slide members being provided with in-turned flanges, weather strips fixed to said framework and provided with resilient edges arranged to engage with said flanges, a window sash, horizontally disposed studs rigidly secured to the lower portions of said sash and received within bearing openings provided in connection with said slide members, a cam element rotatable with one of said studs, a cam plate carried by the outer portion of one of said studs and provided with yieldable engaging edges, said cam plate being movable through a medium of said cam element upon the rotation of said shaft and said studs in a direction longitudinal of said studs to cause the yieldable edges of said cam plate to engage with the resilient edges of said window strips thus holding the sash in a locked position.
- 50 10. In a window structure, a frame provided with a sash opening, guides provided along the vertical sides of said opening, metallic slide members vertically movable in said guides, said slide members being provided with in-turned flanges, weather strips secured to said frame and having the free edges thereof arranged in frictional contact with said flanges, a window sash supported in connection with said slide members, horizontally disposed studs rigidly secured to the lower portions of said sash and received within bearing openings in connection with said slide members, a cam element rotatable with one of said studs, a cam plate carried by the outer portion of one of said studs and pro-

vided with resilient members at certain of its edges, said cam plate being movable through the medium of said cam element upon the rotation of said sash and said studs in a direction longitudinal of said studs to force the resilient members of the cam plate into frictional holding engagement with said weather strips.

11. In a window structure, a hollow slide formed of two substantially channel-shaped members, the two inner legs of said members overlapping and being connected to one another, said inner legs forming the inner sides of the slide, the webs or intermediate portions of said members being adapted to bear against opposite sides of a stile groove, and the two outer legs of said members being adapted to bear against the stile groove base.

12. In a window structure, a frame having a stile groove formed therein, a hollow slide formed of two substantially channel-shaped members, the two inner legs of said members overlapping and being longitudinally connected, said inner legs forming the inner side of the slide, the webs or intermediate portions of said members bearing against opposite sides of the stile groove, and the two outer legs resting adjacent the base of the stile groove on opposite sides of the latter, in combination with means retaining the said outer legs adjacent the stile groove base while permitting longitudinal movement of the slide in its stile groove.

13. In a window structure, the combination of a window frame having stile grooves therein, slides vertically movable in said grooves, a sash pivoted between the slides, at least one slide having an outwardly disposed recess formed longitudinally therein, a brace one extremity of which is pivoted to said sash, the opposite extremity of said brace being in slidable engagement with said recess, and automatic means for engaging said latter brace extremity when said sash is moved pivotally into a predetermined inclined position thereby preventing further movement of said sash.

14. In a window structure, the combination of a window frame having stile grooves therein, slides vertically movable in said grooves, a sash pivoted between the slides, at least one slide having an outwardly disposed recess formed longitudinally therein, a brace one extremity of which is pivoted to said sash, the opposite extremity of said brace being in slidable engagement with said recess, and automatic means for engaging said latter brace extremity when said sash is moved pivotally in either direction through a predetermined inclination thereby preventing further movement of said sash.

15. In a window structure, the combination of a frame having stile grooves therein, slides vertically movable in said grooves, a sash extending between said slides, pins ex-

tending outwardly from said sash by which the latter is supported between said slides, cams positioned outwardly of said slides which are rotated with said pins, resilient members carried by said slides and adapted to be moved outwardly by the rotation of said cams, and bumpers on the outer faces of said members which are moved outwardly against the bases of the stile grooves and thus hold the slides against vertical movement when the sash is turned to a predetermined angle.

In testimony whereof I affix my signature.
JOHN R. STEWART.
